UNITED STATES PATENT OFFICE

NEWELL V. DYER, OF BROCKTON, MASSACHUSETTS, ASSIGNOR TO UNITED SHOE MACHINERY CORPORATION, OF PATERSON, NEW JERSEY, A CORPORATION OF NEW JERSEY

SKIVING MACHINE

Application filed November 15, 1929. Serial No. 407,502.

This invention relates to skiving machines and is herein illustrated as embodied in a skiving machine which comprises a rotary disk knife, a rotary roll for advancing work to the knife, and a presser extending across the roll for holding the work against the roll.

In such a machine the operative face of the presser should be normally substantially parallel to the adjacent surface of the roll and should be so supported that its two ends may yield independently of each other so that a substantially uniform pressure may be applied to the work throughout the portion engaged by the presser. It is desirable that although the foot should yield freely toward and from the feed roll, it should nevertheless resist all tendency to be turned or swung into contact with the knife.

To this end, and in accordance with one feature of the invention, the illustrated presser is carried by a spring having two legs connected by a reverse curve, the legs being fastened to a stationary part of the machine. In the illustrated construction a leaf spring is employed, the legs of the spring being fastened to the usual edge gage block of the machine, with the reverse curved portion projecting over the feed roll; and the presser is fastened to the spring near the reversely curved portion. With this construction the yielding movements of the presser, due to the passing of the work between it and the roll, are compelled to take place in a path substantially perpendicular to the adjacent surface of the roll with no turning or rotating of the foot which might endanger the edge of the knife.

This and other features of the invention including certain details of construction and combinations of parts will be described as embodied in an illustrated construction and pointed out in the appended claims.

Referring now to the accompanying drawings,

Fig. 1 is a front elevation of a portion of a machine in which the present invention is embodied;

Fig. 2 is a plan view showing more particularly the relative positions of the knife and presser;

Fig. 3 is a detail partly in elevation and partly in section showing the action of the presser upon a piece of work which tapers from the body portion toward the edge; and

Fig. 4 is a view similar to Fig. 3 showing the action of the presser upon a piece of work which tapers from the edge toward the body portion.

In the drawings the invention is shown as embodied in the well-known Amazeen skiving machine. In this machine the work is fed against the edge of a rotary disk knife 5 by a rotary feed roll 7 and a rotary feed disk 9, the roll having a cylindrical surface which cooperates with the feed disk and a frusto-conical surface which supports that portion of the work which is being skived. The angle of the scarf produced is determined by the relative positions of the frusto-conical portion of the feed roll and the knife; and it is thus important that the work be pressed firmly and uniformly against the periphery of this portion of the feed roll.

In the construction shown, the margin of the work to be acted upon by the knife is pressed against the frusto-conical portion of the feed roll directly in advance of the edge of the knife by a presser 11 which is brazed to a leaf spring, herein shown as being made in two parts. This spring is of elongated U-shape and comprises two legs 13, 15 connected by a reverse curve 17. For convenience in manufacturing, this spring is made in two parts, as shown, connected by screws 19. The ends of the legs of the spring are fastened by a screw 21 to an edge gage block 23 provided with a gage finger 25, the under face of the gage finger and the adjacent surface of the block being shaped to fit the periphery of the roll. The extreme ends of the legs 13, 15 of the leaf spring, where they are fastened to the edge gage block by the screw 21, are somewhat separated by a spacer 25 through which the screw passes.

The presser 11 is of the usual shape, having a curved front face and a vertical rear face, said latter face being very close to the edge of the knife, as shown in Fig. 2; and it will be clear that, as the work passes through the machine, it should not turn the presser at all

about an axis parallel to the axis of the roll, since in such case the presser will be liable to contact with the edge of the knife. With the presser carried by the reversely curved leaf spring having both of its legs fastened to the stationary edge block, the presser is moved up and down by the work but is prevented from turning or swinging into contact with the knife. In order to ensure that no such turning can take place and to ensure that the leaf spring shall not swing about the axis of its fastening screw 21, an upstanding flange 27, formed upon the edge gage block 23, engages the rear edges of the legs 13, 15 of the leaf spring.

15 In order to permit the presser 11 to be adjusted vertically in accordance with the thickness of the work to be skived, a small thumb-screw 29, threaded through the upper leg 13, passes through a hole in the lower leg 15 and rests upon the upper surface of the edge gage block. A coiled spring 31 encircles the stem of the screw between the head thereof and the upper leg 13, providing sufficient friction to prevent the screw from turning accidentally. By turning the screw the presser may be raised and lowered.

It is desirable to be able to control the force with which the presser holds the work against the roll; and to this end means is provided for varying the effective lengths of the legs of the U-shaped leaf spring, it being obvious that the shorter the legs the more forcibly the presser will engage the work. This means takes the form of a clamp having a lower plate 33 extending beneath a portion of the edge gage block 23, an upper plate 35 located above the upper leg 15 of the leaf spring, a spacer 37 located between the legs, 40 four posts 39, connecting the upper and lower plates 35, 33 upon which the spacer is slidably mounted, and a thumb-screw 41 threaded through the upper plate. By moving the clamp into different positions and manipulating the screw 41, the effective lengths of the legs may be varied to vary the force with which the presser engages the work.

It has been stated above that the presser 11 should be so mounted that the ends may yield independently of each other. For example in Fig. 3, the margin of the work 100 has a thin edge while in Fig. 4 the margin of the work 200 has a thick edge. In both cases, however, it will be seen that the presser 11 engages the work uniformly. In order to improve the operation of the presser, particularly in the case in which, as in Fig. 4, the edge of the work is thicker than the rest of the margin, the lower leg 15 of the spring is made somewhat thinner than the upper leg.

Although the invention has been set forth as embodied in a particular construction, it should be understood that the invention is not limited in the scope of its application to the

particular construction which has been shown and described.

Having thus described my invention, what I claim as new and desire to secure by Letters Patent of the United States is:

1. A skiving machine having, in combination, a knife, a feed roll, a spring having two legs connected by a reverse curve, means for fastening the legs to a stationary part of the machine, and a presser carried by the spring 75 in position to cooperate with the roll.

2. A skiving machine having, in combination, a knife, a feed roll, a spring having two legs connected by a reverse curve, means for fastening the legs to a stationary part of the machine, and a presser fastened rigidly to the spring in position to cooperate with the roll.

3. A skiving machine having, in combination, a knife, a feed roll, a spring having two legs connected by a reverse curve, means for fastening the legs to a stationary part of the machine, a presser carried by the spring, and a stationary member engaging the spring at 85 one side thereof.

4. A skiving machine having, in combination, a knife, a feed roll, a spring having two legs connected by a reverse curve, means for fastening the legs to a stationary part of the machine, and a presser carried by the spring, 95 one leg of the spring being of smaller cross-section than the other.

5. A skiving machine having, in combination, a knife, a feed roll, a spring bent into a reverse curve, means for holding the legs 100 of the spring stationary in a locality remote from the reverse curve, and a presser carried by the spring adjacent to the reversely curved portion in position to hold the work against the roll.

6. A skiving machine having, in combination, a knife, a feed roll, a leaf spring bent into a reverse curve, means for holding the legs 110 of the spring stationary in a locality remote from the reverse curve, and a presser carried by the spring adjacent to the reversely curved portion in position to hold the work against the roll.

7. A skiving machine having, in combination, a knife, a feed roll, a spring of elongated U-shape having its legs fastened to a stationary part of the machine and the portion of the spring which connects the legs projecting over the feed roll, and a presser carried by the spring in position to cooperate with the roll.

8. A skiving machine having, in combination, a knife, a feed roll, a leaf spring of elongated U-shape having its legs fastened to a stationary part of the machine and the portion of the spring which connects the legs projecting over the feed roll, and a presser carried by the spring in position to cooperate with the roll.

9. A skiving machine having, in combina-

tion, a knife, a feed roll, an elongated spring having two legs connected by a reverse curve, means for fastening the legs to a stationary part of the machine, and a presser fastened to the spring adjacent to the reverse curve and located in position to hold the work against the roll.

10. A skiving machine having, in combination, a knife, a feed roll, an elongated leaf spring having two legs connected by a reverse curve, means for fastening the legs to a stationary part of the machine, and a presser fastened to the spring adjacent to the reverse curve and located in position to hold the work against the roll.

11. A skiving machine having, in combination, a knife, a feed roll, an elongated spring having two substantially parallel legs connected by a reverse curve, means for fastening the legs to a stationary part of the machine, and a presser fastened to the spring adjacent to the reverse curve and located in position to hold the work against the roll.

12. A skiving machine having, in combination, a knife, a feed roll, a leaf spring having two legs connected by a reverse curve, means for fastening the legs to a stationary part of the machine, a presser carried by the leaf spring and located in front of the knife and above the roll, and a rigid member for engaging the rear edges of the legs of the spring.

13. A skiving machine having, in combination, a knife, a feed roll, a leaf spring having two legs connected by a reverse curve, means for fastening the legs to a stationary part of the machine, a presser carried by the leaf spring and located in front of the knife and above the roll, and means engaging the spring to prevent the presser from turning about an axis substantially parallel to that of the feed roll.

14. A skiving machine having, in combination, a knife, a feed roll, a spring having two legs connected by a reverse curve, means for fastening the legs to a stationary part of the machine, a presser carried by the spring in position to press the work against the roll, and means engaging the spring for varying the force exerted by the presser upon the work.

15. A skiving machine having, in combination, a knife, a feed roll, a spring having two legs, means for holding portions of the legs stationary, a presser carried by the spring in position to press the work against the roll, and means for varying the effective length of the legs to vary the force exerted by the presser upon the work.

16. A skiving machine having, in combination, a knife, a feed roll, a spring having two legs connected by a reverse curve, means for fastening the legs to a stationary part of the machine, a presser carried by the spring in position to press the work against the roll,

and adjustable means for clamping the legs to each other and to the stationary part of the machine at different localities to vary the force exerted by the presser upon the work.

17. A skiving machine having, in combination, a knife, a feed roll, a spring having two legs connected by a reverse curve, means for fastening the legs in a locality remote from the reverse curve to a stationary part of the machine, a presser carried by the spring adjacent to the reverse curve, and an adjusting member located between the presser and the locality at which the legs are fastened for raising and lowering the free portion of the spring and with it the presser.

18. A skiving machine having, in combination, a rotary knife, a feed roll, an edge gage block, a leaf spring having two legs connected by a reverse curve, means for fastening the legs to the edge gage block with the reversely curved portion of the spring projecting beyond the block, a presser carried by the projecting portion of the spring, and clamping means for varying the effective length of the legs to vary the force with which the presser engages the work.

In testimony whereof I have signed my name to this specification.
